UNITED STATES PATENT OFFICE.

GEORGE WINTHROP COOKE, OF JAMAICA, NEW YORK, ASSIGNOR TO VACUUM OIL COMPANY, OF NEW YORK, N. Y., A CORPORATION OF NEW YORK.

DISPENSING FAUCET.

1,405,099.

Specification of Letters Patent. Patented Jan. 31, 1922.

Application filed May 13, 1920. Serial No. 381,098.

To all whom it may concern:

Be it known that I, GEORGE WINTHROP COOKE, a citizen of the United States, and resident of Jamaica, in the county of Queens 5 and State of New York, have invented certain new and useful Improvements in Dispensing Faucets, of which the following is a specification.

This invention relates to a dispensing faucet, and, as set forth herein, is disclosed more particularly in connection with a faucet for dispensing oil and other similar liquids.

Prominent objects of the invention are the copious flow, simplicity of operation, actuation of the off and on movement of the handle, also avoidance of objectionable leakage, high efficiency, simplification and durability of the construction generally.

With the above and other purposes in view the invention comprehends a novel arrangement of faucet or valve and cork or other flexible lining in communication with a rotary sleeve together with a means for regulating the off and on movement of the sleeve and means of suspending the aforesaid faucet to the inside of a bung.

As previously intimated, the improvement involves other important features which in addition to those alluded to are 30 clearly explained in the subsequent detailed description.

The invention is shown and will be described as adapted for service in connection with an oil barrel for dispensing lubricating oils, but it is understood that the improvements are not restricted to such use.

In the drawings:—

Fig. 1 is a side view, partly in section, of the faucet attached to the inside of the 40 bung;

Fig. 2 is a longitudinal section of the faucet and certain appurtenances;

Fig. 3 is a section on the line 3—3 of Fig. 1; and

Fig. 4 is a section on the line 4—4 of Fig. 1.

Referring more particularly to Fig. 2, the bore or passageway 1 and spout 2 are of uniform diameter. This is made possible 50 by enlarging the rotary valve chamber 3, for the admission of the cork or other flexible lining 4, the bore of the rotary valve 5 being of the same diameter as the passageway 1. The cork or other flexible lining is cut away 55 to register with the spout 2, as shown in Fig.

3, and the rotary valve cylinder 5 is cut away so as to register with the spout 2 when fully open, as in Fig. 3 in the open position of the valve.

The cork or other flexible lining is confined between the shoulder 6, formed by the enlargement of the casing and the shoulder 7, formed on the valve cylinder 5.

I do not confine myself as to the means that may be employed to prevent the flexible lining 4 from turning out of register when the valve cylinder is turned either to the off or on position.

An inwardly projecting pin 8 in the casing enters a slot 9 in the valve cylinder and arrests the turning movement of the latter in a fully open or fully closed position. Said pin also prevents the withdrawal of the valve cylinder when the pressure of the liquid is behind it and facilitates operation. The valve is operated by turning the handle 10.

Owing to the fact that the faucet has a uniform passageway therethrough a faucet of large capacity is obtained without employing a bung of undesirable proportions.

In attaching the faucet to the lug 11, on the under face of the bung 12, the screw end 13 of the faucet fits over the lug and they are bored to receive a cotter pin 14, as shown in Figs. 1 and 4. The lug 11 is made sufficiently long and snug fitting, thus eliminating lateral strains due to rough handling in transportation. The cotter pin 14 prevents the faucet from falling off the bung 11, said pin being withdrawn when the faucet is to be removed from the lug.

I do not limit myself to the particular construction and arrangement of parts shown and described, but reserve the right to all modifications fairly within the scope of my invention.

What I claim as my invention and desire to secure by Letters Patent is:

A faucet comprising a body having a cylindrical bore of uniform diameter extending from one end of the body and a cylindrical chamber at the opposite end of the body of greater diameter than the bore axially aligned with such bore and communicating with the latter and having a wall forming a shoulder connecting the cylindrical wall with the wall of the bore, a spout extending laterally from the chamber and having a diameter equal to the diameter 110

of the cylindrical bore, a valve member fitting in the chamber, having one end abutting the shoulder and provided with two circumferences one of which turns in engagement with the wall of the chamber near the outer end of the latter, and the other of which is smaller than the bearing portion and connects with the bearing portion through a shoulder, the smaller portion being provided with a lateral spout of a diameter equal to the bore and the aligned spout and adapted to be aligned with the spout, the

valve member having a chamber axially aligned with the bore and having a diameter equal to the diameter of the bore, and a 15 packing surrounding the smaller circumference of the valve member, abutting the shoulder on the latter and also the shoulder between the enlarged chamber of the body and the cylindrical bore, said packing turning with the valve member and having an opening coincident with the opening in the valve member.

GEORGE WINTHROP COOKE.
